EXTENSIBLE UTILITY SHELF

Andrew H. Gerhardt, Chicago, Ill., assignor to
 Electric Household Utilities Corporation, Chi-
 cago, Ill., a corporation of Illinois

Application March 14, 1936, Serial No. 68,848

13 Claims. (Cl. 211—143)

This invention relates to improvements in extensible utility shelves for tablelike supports and more particularly for supports or tables for operating mechanisms, such as household ironers 5 and the like.

One object of the invention is to provide an extensible utility shelf of rugged design, together with means for firmly supporting the same in all the positions of adjustment.

10 Another object of the invention is to provide an extensible utility shelf, as set forth in the preceding paragraph, which is slidably mounted and supported in such a manner as to effectively prevent binding thereof in its sliding movements.

15 A still further object of the invention is to provide a utility shelf of the character set forth, in the form of a grate in which the bars or slats forming the grate are bound together in such a manner as to prevent rattling thereof.

20 Other objects of the invention will more clearly appear from the description and claims herein-after following.

In the drawings forming a part of this specification, Fig. 1 is a horizontal sectional view 25 through the top of a supporting structure, such as a table, illustrating my improved utility shelf structure in connection therewith, the shelf being shown as housed in said table top.

Fig. 2 is an enlarged transverse vertical sec- 30 tional view, corresponding substantially to the line 2—2 of Fig. 1, said view being broken to accommodate the same to the sheet of the drawing.

Fig. 3 is a view similar to Fig. 1, showing the shelf in extended position.

35 Fig. 4 is a vertical sectional view, correspond- ing substantially to the line 4—4 of Fig. 3.

Fig. 5 is an end elevational view, looking from right to left in Fig. 4, with the extensible shelf omitted, said view being on a reduced scale.

40 In said drawings, 10 indicates one end portion of a table having a supporting leg structure 11. The table 10 is of the type usually employed in connection with power-driven household ironers, and in Fig. 5 part of the base of a pedestal or head 45 which supports the ironer roll and cooperating shoe is shown, said pedestal or head being indicated by 12. As shown, the table 10 is formed of heavy sheet metal and the top thereof is of hollow construction, having a top wall 13, spaced side walls 14—14, and transverse end walls, only one of which is shown, the same being indicated by 15. The spaced side walls 14—14 have laterally inturned bottom flanges 114—114. The table top is open at the bottom, as indicated at 16. The 50 end wall 15 is provided with a plurality of hori-

zontally disposed openings or slots 17—17, which are arranged in series and are spaced, as shown most clearly in Fig. 5. At opposite sides, adjacent to the ends of the end wall 15, are provided vertical slots 18—18.

55 My improved extensible shelf, which is indicated by A, is normally housed within the table top and is slidable outwardly for use. In Figs. 3 and 4, the utility shelf A is shown in fully ex- 10 tended position. This shelf is in the form of a grate, formed by horizontally disposed, spaced, flat metal slats 19—19 mounted in a frame 20. The frame 20 is of substantially rectangular out- 15 line and comprises transverse front and rear sec- tions 21 and 22 and side sections 23—23 connect- 20 ing said front and rear sections. The frame 20 is composed of two bars, which are of rectangular cross section. One of said bars forms the front section 21 and the side sections 23—23 of the frame, and the other bar forms the rear section 22 thereof. The bar forming the front section is bent to provide the side sections 23—23, which are disposed at substantially right angles to said front section 21. The side sections 23—23 extend rearwardly beyond the main portion of the rear section 22, as indicated at 24—24, said exten- 25 sions 24—24 being fixed to rearward extensions 25—25 on the section 22. The extensions 25—25 are portions of the same bar which forms the sec- 30 tion 22, the opposite end portions of said bar being bent rearwardly at right angles to form said extensions 25—25. As shown most clearly in Fig. 4, the bar forming the section 22 of the frame 20 is elevated with respect to the front section 21 and the side sections 23—23 of said frame 20, and said extensions 24—24 are offset upwardly with respect to the side sections 23—23 into alignment with the extensions 25—25 of the bar forming the rear section 22 of the frame 20 and are secured to said last named extensions by screws 26—26. The extensions 25—25 project beyond the rear extremities of the extensions 24—24 and carry anti-friction guide rollers 27— 35 27. As most clearly shown in Fig. 1, each roller 27 is rotatably mounted on a short stub shaft 28 having a reduced portion extending through an opening in the outer end of the corresponding extension 25 and riveted over at its extremity. The stub shaft 28 projects outwardly beyond the roller to form a guide member 29. The portion of the stub shaft 28 which forms the guide member 29 is of greater diameter than the bearing portion of said shaft, on which the roller 27 is mounted and has its outer end face rounded off, as shown. The guide rollers 27—27 have rolling engagement 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

with the under surface of the top wall 13 of the table and the guide projections 29-29 cooperate with the side walls 14-14 to guide the shelf A for straight line movement. In this connection, 5 it is pointed out that the inturned flanges 114-114 on the side walls of the table serve as emergency supporting means for the inner end of the shelf A. These flanges act as supports for the rollers 27-27 should the inner end of the shelf 10 droop when the shelf is pushed fully into the table.

The outer ends of the side sections 23-23 of the frame 20 are inclined inwardly toward each other where they join the front section 21, as indicated at 30-30. The sections 30-30 form 15 friction wedge elements, which serve to hold the shelf seated in its innermost position, as herein-after more fully pointed out.

The slats 19-19 of the shelf A are connected to the front and rear sections 21 and 22 of the frame 20. The slats 19-19 have their front ends turned downwardly at right angles and said downwardly bent portions are riveted to the inner side of the section 21, as shown most clearly in Fig. 4. The rear ends of said slats 19-19 extend through 25 slots provided in the rear section 22 of the frame 20 and are thus supported by said section 22.

To prevent rattling of the slats 19-19, the rear end sections thereof are bound by a wire or rod 31 having hook extremities 32-32, which are 30 anchored to the outermost slats at opposite sides of the shelf A. The wire 31 passes alternately over and under successive slat members, thereby holding the same against rattling, which might otherwise occur due to vibrations transmitted 35 through the table from the operating mechanism mounted thereon.

As shown in Figs. 1, 3, and 4, the front and rear sections 21 and 22 of the frame 20 are located respectively in front and in back of the end wall 40 15 of the table, and the slats 19-19 and the side sections 23-23 extend through the slots of said end wall, the slats extending through the horizontal slots 17-17 and the side sections extending through the vertical slots 18-18. These 45 slats thus serve as guide means for the shelf and direct it in its movements inwardly and outwardly of the table.

In assembling the shelf A with the table, the front and side sections 21 and 23-23 of the frame, 50 with the slats 19-19 attached thereto, are applied to the table before the bar forming the rear section 22 is secured to said side sections 23-23. In said assembling operation, the rear portions 55 of the side sections 23-23 of the frame 20 and the rear portions of the slats 19-19 are first engaged through the openings in the end wall 15 of the table. The bar forming the rear section 22 of the frame 20 with the rollers 27-27 thereon is then applied by engaging the extremities of the 60 slats 19-19 through the openings in said rear section 22 and securing the rearward extensions 25-25 to the extensions 24-24 of the side sections 23-23. The anti-rattling wire 31 is then applied to the slats 19-19.

65 As will be evident upon reference to Fig. 1, when the shelf is in its innermost position, that is, when the same is completely housed in the table, the inclined friction wedge sections 30-30 of the side sections 23-23 of the frame 20 will have 70 wedging engagement with the inner vertical edge walls of the guide slots 18-18 of the end wall 15 of the table, thus frictionally retaining the shelf in its innermost position and preventing accidental outward movement of the same.

75 To extend the shelf A, the same is forcibly

pulled outwardly. During this outward movement, the shelf is guided by the side sections 23-23 and the slats 19-19 working in the slots 18-18 and 17-17, and by the rollers 27-27 and the guide members 29-29 engaging respectively the top wall and the side walls of the table. The guide members 29-29 by engagement with the side walls of the table effectively prevent sidewise of the shelf, and the rollers 27-27 by engagement with the top wall of the table hold the shelf against drooping or sagging with respect to the table top.

From the preceding description taken in connection with the drawings, it will be evident that I have provided an extensible utility shelf which is rigidly supported in all positions of adjustment thereof, the slats 19-19 and the side members 23-23 engaging through the slots of the end wall 15 of the table furnishing support throughout the width of the shelf, and in connection with the rollers on the extreme ends of the extensions 24-25 and 24-25 of the side sections 23-23 and the rear section 22 of the frame providing ample support against downward tilting of the shelf, the extremities 24-25 and 24-25 acting as levers 25 bracing said shelf in all positions thereof.

I have herein shown and described what I now consider the preferred manner of carrying out my invention, but the same is merely illustrative and I contemplate all changes and modifications that come within the scope of the claims appended hereto.

I claim:

1. In a structure of the character described, the combination with a table member having a hollow top; of an extensible utility shelf; and means for slidably guiding said shelf with respect to the table including supporting means engaging beneath said shelf, and rearwardly extending arms on said shelf having sliding bearing engagement with the under side of said table top inwardly of said supporting means.

2. In a structure of the character described, the combination with a table having a top wall; of an extensible utility shelf; means at the end of the table engaging beneath said shelf for slidably supporting the same; a rearward extension on said shelf; and guide means on said extension engaging the top wall of the table inwardly of said supporting means for bracing the shelf.

3. In a structure of the character described, the combination with a table having a top wall and side walls at opposite sides thereof below said top wall; of an extensible utility shelf slideable beneath said top wall; and rearward extensions on said shelf having bearing engagement with said side walls and under side of said top wall for respectively guiding said shelf for straight line movement and supporting it at any position of adjustment.

4. In a structure of the character described, the combination with a table having a top wall and side guide members; of an extensible utility shelf including side members extending rearwardly from said shelf, said shelf being slideable beneath said top wall; supporting guide means on said table engaging beneath said shelf; roller-supporting stub shafts on said rearwardly extending side members projecting laterally therefrom and guided between said side guide members; and rollers journaled on said shafts and having rolling engagement with the under side of said top wall.

5. In a structure of the character described, the combination with a supporting member hav-

ing a top wall and spaced side walls; of an extensible shelf slidable beneath said top wall, said shelf including a frame having longitudinally disposed side members, said side members having laterally inwardly directed gripping portions; and means on said supporting member adapted to be gripped between said inwardly directed portions to frictionally hold said shelf in its innermost position.

10. 6. In a structure of the character described, the combination with a supporting tablelike member having a top wall, spaced side walls, and an end wall, said end wall having guide openings therethrough at opposite sides thereof; of a rectangular shelf including a frame structure comprising spaced, longitudinally extending side members engaged through and being slidable in said openings, said side members having laterally inwardly directed wedge sections at their outer ends adapted to be wedged against the inner side walls of said openings to frictionally hold said shelf in its innermost position.

7. In a structure of the character described, the combination with a tablelike supporting member having a substantially horizontal abutment surface and a top wall and a vertical end wall, said end wall having openings therethrough at opposite sides thereof; of an extensible shelf slidable beneath said top wall, said shelf including a frame comprising a transverse front member, longitudinally extending side members, and a transverse rear member connecting said side members, said rear member being disposed on the inner side of said end wall of the supporting member, and means connected to said rear member adapted to engage said abutment surface of the table-like member to support the shelf in its extended position.

40. 8. In a structure of the character described, the combination with a tablelike supporting member having a vertical end wall, said end wall having openings therethrough at opposite sides thereof and a transversely arranged series of openings between said first named openings; of an extensible shelf in the form of a grate member having a transverse front section, side sections extending rearwardly from said front section, and slat members between said side sections extending rearwardly from said front section, said side sections extending through said first named openings and being slidably guided therein, and said slat members extending through said second named openings and being slidably guided therein.

9. In a structure of the character described, the combination with a tablelike supporting member having a substantially horizontal abutment surface and a vertical end wall; of an extensible shelf carried by said supporting member, said shelf being in the form of a grate member comprising a plurality of longitudinally extending, laterally spaced, supporting elements, said end wall of the supporting member having 65 openings therethrough slidably accommodating

said elements, and means connected to the inner end of said shelf adapted to engage said abutment surface of the table-like member to support the shelf in its extended position.

10. In a structure of the character described, the combination with a tablelike supporting member having a vertical end wall section, said end wall section being provided with a series of openings therethrough; of an extensible shelf of substantially rectangular shape including longitudinally extending, spaced slats and a frame member supporting said slats, said frame member having transverse front and rear sections and connecting side sections, said front and rear sections being disposed respectively on the outer and inner sides of said end wall, said slats extending between and being anchored to said front and rear sections of the frame member, said side sections of the frame member and said slats being slidably guided in said openings of said end wall.

11. In a slidable shelf structure, the combination with a rectangular frame member comprising front and rear sections connected by side sections; of a plurality of laterally spaced, longitudinally extending supporting slats fixed to said front section and extending through and being supported in openings provided in said rear section; and a binding wire anchored to the outermost slats at opposite sides of said shelf, said wire being in gripping engagement with all of said slats.

12. In a slidable shelf structure, the combination with a rectangular frame member comprising front and rear sections connected by side sections; of a plurality of laterally spaced, longitudinally extending supporting slats fixed to said front section and extending through and being supported in openings provided in said rear section; and a transversely arranged, binding wire engaging said slats adjacent their rear ends, said wire extending alternately over and under adjacent slats and having its extremities hooked, anchored engagement with the outermost slats at opposite sides of said shelf.

13. In a structure of the character described, the combination with a table-like supporting member having a top wall and a vertical end wall, said end wall having a horizontally extending series of slots formed therein; of an extensible shelf slidable beneath the top wall, said shelf comprising a transverse front member and a plurality of horizontally spaced apart slats connected to said front member and extending through and being supported in said slots, additional means for assisting in supporting said slats and for maintaining them in a substantially horizontal plane at substantially all positions of horizontal adjustment of said shelf, and cooperating means carried on one or more of said slats and on one of said walls for limiting the outward movement of said shelf relative to said supporting member.
